UNITED STATES PATENT OFFICE.

HANS P. VON NOSTITZ, OF NEW YORK, N. Y.

DESIGN FOR BRAID.

SPECIFICATION forming part of Design No. 36,188, dated January 6, 1903.

Application filed December 10, 1902. Serial No. 134,707. Term of patent 3½ years

To all whom it may concern:

Be it known that I, HANS P. VON NOSTITZ, a citizen of the United States, residing in New York, borough of Brooklyn, and State of New York, have invented a new, ornamental, and original Design for Braid, of which the following is a specification, reference being had to the accompanying drawings, forming a part thereof.

- 10 The drawings show part of a braid embodying my design. The general features of the braid consist of enlarged polyfoil portions that are spaced apart at regular intervals and connected by narrow or band portions. The enlarged portions are substantially quadrifoil in form and are somewhat longer in one direction than in the other and are connected in the direction of their length by the centrally-disposed rectangular band portions *b*. The enlarged portions are braided, with their meshes forming symmetrical rows *c* on opposite sides of the longitudinal axis of the braid. These rows are arc-shaped in each lobe of the enlarged portion and extend in general parallel direction with each other and with the axis of the braid. The meshes at the transverse center line of the lobes of the quadrifoil portion are somewhat larger than the meshes at the ends.
- 25 30 The major and minor axis of the enlarged

portions extend, respectively, longitudinally and transversely of the braid, and the meshes of the lobes on the major axis connect with the parallel rows *d* of meshes of the rectangular band portions *b*. The outline of the braid forms an ornamental design; but in addition to this the arrangement of the rows of interwoven strands of braiding material increases the ornamental effect by the symmetrical disposition of the arc-shaped and straight rows of meshing. The braiding material when of a silky or glossy character by the variation of the surfaces of the interwoven strands produces reflections and contrasts of the light that bring out the characteristic arrangement of the rows of meshes and enhance the pleasing effect of the design.

Having thus described my invention, what I claim as new, and desire to secure by Letters Patent, is—

The ornamental design for braid as herein shown and described.

In testimony that I claim the foregoing as my invention I have signed my name in presence of two subscribing witnesses.

HANS P. VON NOSTITZ.
